United States Patent Office

Des. 223,457
Patented Apr. 18, 1972

223,457

FLAG

Bruce Romanoff, 32 Court St., Brooklyn, N.Y. 11201
Filed May 22, 1970, Ser. No. 23,099

Term of patent 14 years

Int. Cl. D11—05

U.S. Cl. 29—17

The single figure of the drawing is a view of one face of the flag, the face not shown is identical with said one face.

The drawing has been lined for color.

I claim:

The ornamental design for a flag, as shown and described.

References Cited

UNITED STATES PATENTS

D. 55,275	5/1920	Ivy	-----	D29—17
D. 57,366	3/1921	Masline	-----	D29—17
D. 60,813	4/1922	Ragsdale	-----	D29—17

LOIS S. LANIER, Primary Examiner